UNITED STATES PATENT OFFICE.

CLARENCE A. KISSEL, OF DETROIT, MICHIGAN.

AUTOMATIC TRAIN STOP.

Application filed February 20, 1922. Serial No. 538,067.

To all whom it may concern:

Be it known that I, CLARENCE A. KISSEL, a citizen of the United States, residing at Detroit, in the county of Wayne and State 5 of Michigan, have invented new and useful Improvements in Automatic Train Stops, of which the following is a specification.

This invention relates to a mechanically operated mechanism for automatically stopping trains, and an object of the invention 10 is to provide a comparatively simple mechanism, by means of which a train may be stopped automatically, for the purpose of preventing accidents and further to provide 15 a device which will eliminate the use of de-railers as serious accidents often result from the de-raliment of a train by the approved type of de-railers, used in connection with railway trains.

20 Another object of this invention is to provide a train stop mechanism as specified which comprises a weighted lever connected to the throttle of a locomotive engine, which lever is normally held in position to permit 25 operation of the engine, and also to provide a simple mechanically operated structure for releasing said weighted lever to permit it to move upon its pivot for operating the throttle to arrest movement of the engine 30 equipped with the device.

A further object of this invention is to 35 provide a simple track carried mechanism which may be manually set for operating the train carried mechanism at the proper time to arrest travel of the train, it being understood that the track operated mechanism is placed on the track at the proper 40 distance from a crossing or other dangerous place along the railroad so as to permit the stopping of the train before it reaches such dangerous place.

Other objects of the invention will appear 45 in the following detailed description taken in connection with the accompanying drawings wherein:

Fig. 1 is a side elevation of the cab or engine carried mechanism.

Fig. 2 is a detail section through the cab or engine carried mechanism taken on the 50 line 2—2 of Fig. 1.

Fig. 3 is a top plan of the track carried mechanism.

Fig. 4 is a detail section of the track carried mechanism taken on the line 4—4 of 55 Fig. 3.

Fig. 5 is a detail section taken on the line 5—5 of Fig. 3.

Referring more particularly to the drawings, the improved automatic train stop comprises a lever 1 which is pivotally supported intermediate its ends as shown at 2 from a suitable supporting bracket 3. One end of the lever 1 is connected by means of the slot and pin connection 4 with the steam control structure 5 of any approved type of 60 steam locomotive. A weight 6 is mounted upon the end of the lever 1 remote from the slot and pin connection 4 and the weight is such as to move the outer end of the lever 5 downwardly for operating the mechanism 65 5 to cut off the supply of steam to the cylinders of the locomotive for the purpose of stopping the locomotive equipped with the device.

The lever 1 has an arm 7 pivotally connected thereto which is in turn pivotally connected to a lever 8. The lever 8 is pivotally supported intermediate its ends by a suitable support 10 and it has its end remote 70 from the link 7 provided with a recess 11 75 normally receiving a locking pin 12 for preventing pivotal movement of the lever 8 and consequently preventing pivotal movement of the lever 1. The locking pin 12 is urged into the recess 11 by a spring 13 80 which is coiled about the shank 14 of the pin, and engages against the enlargement 15 and the bearing 16 of the support 17. A spreader wedge 19 is formed upon the upper 85 end of the vertically movable rod 20 which 90 engages between the projection 15 and the pressure roller 21 which is carried by the lever 8. The lower end of the rod 20 has a collar or cuff 22 mounted thereon which 95 aligns with a similar collar or cuff 23 carried by the upper end of the operating rod 24. The operating rod 24 projects downwardly beneath the engine equipped with the structure and has a roller 25 on its lower 100 end which is adapted to be engaged by the operating member 27, of the track structure generically indicated by the numeral 28.

The track structure 28 comprises a suitable supporting plate 29 which is carried by certain of the rail supporting ties A intermediate the rails B, as clearly shown in Fig. 3 of the drawings. The operating member 27 is pivotally supported by means of a slot and pin connection as shown at 30 from the plate 29 and an eccentric 31 engages beneath 105 110 the plate 29.

the free end of the operating member 27. The eccentric 31 is mounted upon a shaft 32 which extends transversely of the track structure and which is connected by miter or bevel gears 33 with a shaft 34 which extends longitudinally of the track structure. The shaft 34 may be of any length and if necessary a suitable coupling as shown at 35 may be embodied in this construction. A hand lever 37 is carried by the shaft 34 to permit manual rocking or rotation of the shaft to rotate the shaft 32 to rotate the eccentric 31 for the purpose of raising the operating member 27 into striking position relative to the roller 25, the said position being indicated in dotted lines in Fig. 4 of the drawings.

In case of danger to the train approaching the track structure 27, the hand lever 36 is operated for rocking the eccentric to move the operating member 27 into its upward operating position, and a train approaching the danger point, and carrying the improved mechanism illustrated in Figs. 1 and 2 of the drawings will be stopped through the engagement of the roller 25 with the member 27. When the roller 25 engages the member 27, it will move the rod 24 upwardly forcing the cuff or collar 23 into the cuff or collar 22 and move the rod 20 forcing the spreading wedge 19 between the roller 21 and projection 15 for moving the locking pin 12 out of the recess 11 for releasing the lever 8 which in turn releases the lever 1 permitting it to move along under gravity action upon the weight 6 and operating the mechanism 5 for arresting travel of the train.

It is, of course, to be understood that the invention may be constructed in other manners and the parts associated in other relations and, therefore, I do not desire to be limited in any manner except as set forth in the claims hereunto appended.

Having thus described my invention what I claim is:

1. In an automatic train stop, the combination with the control mechanism of a locomotive, of a pivotally mounted weighted lever, a second pivotally mounted lever connected thereto, means associated with said second lever for restraining said weighted lever from movement, a vertically movable releasing rod for releasing said restraining

means, and track carried means for operating said rod. 55

2. In an automatic train stop, the combination with the control mechanism of a locomotive, of a pivotally mounted weighted lever connected thereto, a second pivoted lever connected to said first named lever, a locking pin for restraining movement of said second lever, and said weighted lever, and a releasing rod for releasing said locking pin. 65

3. In an automatic train stop, the combination with the control mechanism of a locomotive, of a pivotally mounted weighted lever connected thereto, a second pivoted lever connected to said first named lever, a locking pin for restraining movement of said second lever, and said weighted lever, a releasing rod for releasing said locking pin, a track mechanism comprising an eccentric, an operating striking member adapted to be moved by said eccentric for operating said releasing rod. 75

4. In an automatic train stop, the combination with the control mechanism of a locomotive, of a pivotally mounted weighted lever, a second pivotally mounted lever connected thereto, means associated with said second pivotally mounted lever for restraining said weighted lever from movement, and means for releasing said restraining means. 85

5. In an automatic train stop, the combination with the control mechanism of a locomotive, of a pivotally mounted weighted lever, a second pivotally mounted lever connected thereto, a locking pin co-acting with said second lever for restraining movement of said weighted lever, a spreader wedge for shifting said pin to release said weighted lever, and track carried means for operating said wedge. 95

6. In an automatic train stop, the combination with the control mechanism of a locomotive, of a pivotally mounted weighted lever, a second pivotally mounted lever connected thereto, a locking pin co-acting with said second lever for restraining movement of said weighted lever, an operating rod, a spreader wedge on said operating rod and engaging said pin for shifting the pin to release said weighted lever, and means for operating said rod. 100

In testimony whereof I affix my signature.
CLARENCE R. KISSEL.
